A. L. BUSCH.

SUBMARINE TORPEDO TUBE CONSTRUCTION.

APPLICATION FILED APR. 14, 1917.

1,305,876.

Patented June 3, 1919.

Arthur L. Busch, INVENTOR
Prudelle Wright Small BY ATTORNEY

UNITED STATES PATENT OFFICE.

ARTHUR L. BUSCH, OF ELIZABETH, NEW JERSEY, ASSIGNOR TO SAMUEL L. MOORE & SONS CORPORATION, OF ELIZABETH, NEW JERSEY, A CORPORATION OF NEW JERSEY.

SUBMARINE TORPEDO-TUBE CONSTRUCTION.

1,305,876.

Specification of Letters Patent. Patented June 3, 1919.

Original application filed October 19, 1915, Serial No. 56,656. Divided and this application filed April 14, 1917. Serial No. 162,119.

To all whom it may concern:

Be it known that I, ARTHUR L. BUSCH, of Elizabeth, in the county of Union, and in the State of New Jersey, have invented a 5 certain new and useful Improvement in Submarine Torpedo-Tube Construction, and do hereby declare that the following is a full, clear, and exact description thereof.

My invention relates particularly to sub- 10 marine boats, and is adapted especially for submarine boats designed and used for purposes of war.

The object of my invention is to provide a submarine which is compact, and which 15 may be, if desired, of comparatively small size so that the same can be carried upon or in battleships or cruisers, and which may also be used in shallow waters.

A further object of my invention is to locate the torpedo tubes in such a manner as 20 to provide an advantageous arrangement of the space within the submarine, said torpedo tubes being preferably located at least in part outside of the curvature of the main 25 portion of the hull.

This application is a division of my co-pending application, Serial No. 56,656, filed October 19, 1915, and entitled Submarine.

While my invention is capable of embodiment in many different forms, for the purposes of illustration I have shown only one form thereof in the accompanying drawings, in which—

Figure 1 is a plan view of a submarine 35 made in accordance with my invention; and Figs. 2, 3, 4 and 5 are sectional views taken respectively on lines 2—2, 3—3, 4—4 and 5—5, Fig. 1, looking in the direction of the arrows.

In the drawings I have shown a submarine 40 having a hull portion 1, the walls of which have a general regular curvature, that is, the cross-section of the submarine may be of a general circular, or elliptical shape as 45 shown in Figs. 2 to 5. As the particular character of the whole submarine construction is not essential to the present invention, the same will not be described in greater detail.

In order to provide as small a displacement 50 as possible, and to economize space in the interior of the hull, I arrange the torpedo tube, or tubes, so that the space within the hull is not taken up to any extent

thereby, and at the same time the displacement of the submarine is not unduly increased. 55

At the point where the torpedo tube 2 is to be located, the adjacent portion of the hull is bulged outwardly beyond the general curvature of the hull to provide a pocket 3, the walls 4 inclose the tube as closely as practicable. In the form illustrated, this pocket is formed by a trough-like section 4 of the casing, suitably secured to the remainder of the hull 1 which latter is of regular curvature. It is also advantageous to arrange the pocket 3 at the top of the submarine, and with its axis substantially 60 in a central longitudinal plane, as shown in 70 the drawings.

Although my invention may be employed in connection with any desired number of 65 torpedo tubes, it is particularly adapted to a construction in which two opposed tubes 75 are located in line with each other. In the form illustrated a second torpedo tube 5 is located in line with the tube 2, and the bulged-out portion 4 of the hull is made to extend substantially the entire length of the 80 submarine so as to provide a pocket 3 which is long enough to receive both tubes 2 and 5. 85

With the submarine constructed in accordance with the invention above described, it will be noted that the torpedo tube, or 90 tubes, do not project to any extent into the space within the hull and yet the total displacement of the submarine is not unduly increased, since the pocket provided by the bulged-out walls takes up no more 95 volume than is absolutely necessary. The above features of the construction are particularly advantageous in types of boats which are to be auxiliary to larger craft, or to be operated in shallow water, or with a 100 small numbered crew.

While I have described a specific form of the invention, it will be obvious that many changes may be made without departing from the principle thereof, as defined in the 105 appended claims.

I claim:—

1. In a submarine, the combination of a 110 hull having a general regular curvature, a torpedo tube located within said hull and closely adjacent the walls thereof along substantially its entire length, that portion of the hull which incloses said tube being

bulged outwardly beyond the general curvature of the hull, to provide a pocket containing said tube.

2. In a submarine, the combination of a hull having a general regular curvature, a torpedo tube located within said hull and closely adjacent the walls thereof along substantially its entire length, the axis of said tube being disposed substantially in a central longitudinal plane and at the top of the submarine, that portion of the hull which incloses said tube being bulged outwardly beyond the general curvature of the hull, to provide a pocket containing said tube.

15 3. In a submarine, the combination of a hull having a general regular curvature, a torpedo tube located within said hull and closely adjacent the walls thereof along substantially its entire length, that portion 20 of the hull which incloses said tube being bulged outwardly beyond the general curvature of the hull, to provide a pocket containing said tube, and a similarly arranged, oppositely directed torpedo tube located in line with said first mentioned tube.

4. In a submarine, the combination of a hull having a general regular curvature, a torpedo tube located within said hull and closely adjacent the walls thereof along substantially its entire length, the axis of said tube being disposed substantially in a central longitudinal plane and at the top of the

submarine, that portion of the hull which incloses said tube being bulged outwardly beyond the general curvature of the hull, to 35 provide a pocket containing said tube, and a similarly arranged, oppositely directed torpedo tube located in line with said first mentioned tube.

5. In a submarine, the combination of a 40 hull having a general regular curvature, a portion of the walls of said hull in a plane parallel to the longitudinal axis of the submarine, being bulged outwardly beyond the general curvature of the hull to provide a 45 longitudinal pocket extending substantially the entire length of the submarine, and a pair of oppositely extending torpedo tubes located in said pocket.

6. In a submarine, the combination of a 50 hull having a general regular curvature, the portion of the walls of said hull above its longitudinal axis being bulged outwardly beyond the general curvature of the hull to provide a longitudinal pocket extending 55 substantially the entire length of the submarine, and a pair of oppositely extending torpedo tubes located in said pocket.

In testimony that I claim the foregoing I have hereunto set my hand.

ARTHUR L. BUSCH.
